UNITED STATES PATENT OFFICE.

EDWARD SANKEY, OF BARROW-IN-FURNESS, ENGLAND.

PHOTOGRAPHIC-PRINTING MACHINE.

Application filed January 18, 1923. Serial No. 613,513.

To all whom it may concern:

Be it known that I, EDWARD SANKEY, a subject of the King of Great Britain and Ireland, and resident of 88 Duke Street, 5 Barrow-in-Furness, England, have invented certain new and useful Improvements in Photographic-Printing Machines, of which the following is a specification.

This invention relates to photographic printing machines and more particularly to what are known as bromide printing boxes, its object being to provide simple and efficient means for printing individual positives in a rapid and economical manner.

15 Usually a light box is employed on which the negative is carried. The operator places the bromide paper or card over the negative, there being suitable setting gauges for the purpose of ensuring correct positioning, 20 and a movable platen is then brought down upon the bromide paper to hold it in firm contact with the negative whilst the light is switched on for the requisite period.

25 My invention comprises the improved platen operating and light controlling mechanism hereinafter described and claimed.

Referring to the accompanying sheet of explanatory drawings:—

30 Figure 1 is a side elevation and Figure 2 an end elevation of a photographic printing machine constructed according to this invention.

The same reference letters in the two views indicate the same parts.

In accordance with my invention, the platen *a* is operated mechanically and carried by a stem *b* supported by a collar *i* which rests normally on one of the collars *i*¹ 40 on trunnion pieces pivotally carried by two radius links or arms *c* and *d* which are themselves pivotally attached to the frame of the machine at *e* and *f* respectively. The platen is pressed towards the negative, 45 mounted on the sloping top of the light box *g*, by a compression coil spring *h* coiled around the platen stem. The collar *i* limits the outward movement of the platen under the spring action.

50 The lower arm *d* has a lug-like projection *d*¹ thereon on its underside, which is adapted to engage or rest upon a corresponding projection upon a rocking or swinging member *j* fulcrumed about the pivot *f* of the said lower arm, and having a roller *k* thereon engaged by a cam groove *l* which may be

formed in a plate attached to the inner side of the worm wheel *m*. The said inter-engaging cam and roller serve to actuate the platen *a*, but the necessary pressure between 60 the bromide paper and the negative is applied through the medium of the lever *n* which, with an adjustable spring *o*, is pivoted upon the lower arm *d*. One end of the 65 said lever *n* is, as shown at Figure 1, engaged or in abutment with the upper extremity of the aforesaid rocking member *j* so that when the said member moves in the direction to lower the platen, pressure is applied to the arm *d* and hence to the platen *a*. 70 The inter-engaging or abutting faces of the 75 said lever *n* and rocking member *j* are shaped as shown, so that if the platen meets an obstruction, the resistance of the lower arm to movement under the action of the 80 rocking member causes the end of the lever to rise clear of the operative end of the said member. The latter can then continue to oscillate without the platen being brought into contact with the negative. This arrangement acts as a safety device to prevent 85 the hand of the operator being trapped and damaged or an article being forced so firmly against the negative as to break the same.

In addition to the cam groove *l* before referred to, whereby the platen is operated, I provide two similar cam plates, *p*, *p*¹ (the plate *p* being fixed to the wheel *m* while the plate *p*¹ is adjustably secured to the wheel *m* by bolts projecting through elongated 90 slots *p*² (see Fig. 1) in the cam plate *p*¹). The said cam plates rotate in unison with the wheel *m* carrying the cam groove *l* and serve to actuate the lever *q*, by which the switch for the electric lamp in the light box 95 *g* is opened and closed. By adjusting the said cam *p* the period during which the light is switched on in the light box can be varied to suit the character or quality of the negative from which prints are being made. A 100 master switch (not shown) is provided for the operator to prevent the light being switched on.

The worm wheel *m*, in the example illustrated, is adapted to be actuated through 105 worm *r* and other gearing by an electric motor or other source of power at a speed which is governed by the rate at which the operator can feed the bromide sheets or cards to the machine.

In practice, the platen is brought into contact with the negative before the down-

ward movement of the link *d* is completed, the remainder of such movement increasing the pressure applied to the negative through the spring *h*. The compression of the latter can be adjusted by the knurled nut *s*. It will be seen therefore that no direct mechanical pressure is applied to the negative but only the yielding pressure applied through the spring *h*. The spring *o* is of such a strength that it does not yield to allow the lever *n* to turn about its fulcrum until the spring *h* has been compressed to practically its maximum extent.

The light box may be of any convenient construction and may be secured, as shown, upon a bracket of the platen operating mechanism, suitable adjustable connecting rods serving to clamp the light box in place.

I claim:

1. In photographic printing machines, the combination comprising a platen, a stem carrying said platen, radius links having the said stem in pivotal connection therewith, a spring mounted on the stem above the platen, and below said radius links, a collar fixed upon the said stem and normally sup-

porting same, power actuated means for vibrating the said links, and means preventing the trapping of the hand of the operator and the imposition of undue pressure on the negative, as set forth.

2. In photographic printing machines, the combination comprising a platen, a stem carrying said platen, radius links having the said stem in pivotal connection therewith, a spring mounted on the stem above the platen and below said radius links, a collar fixed upon the said stem and normally supporting same, a power actuated rocking member engaging one of said links, and means permitting the said member to continue in movement without transmitting movement to said link, as set forth.

3. In photographic printing machines, the employment with the combination claimed in claim 1, of means for automatically switching on the printing light at the appropriate times and for varying the extent of such lighting periods, as set forth.

In testimony whereof I have signed my name to this specification.

EDWARD SANKEY.
